HARRY WEARNE, OF RIXHEIM, GERMANY.

DESIGN FOR WALL-PAPER.

SPECIFICATION forming part of Design No. 31,960, dated December 5, 1899.

Application filed November 11, 1899. Serial No. 736,695. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a plan view of a strip of wall-paper embodying the features of my design.

The design consists of the representation of a bunch of large roses and buds and leaves of

the same and sprays of roses of a smaller type, which sprays include flowers, buds, and leaves and extend from the main bunch upwardly and in opposite directions.

Having thus described my invention, I claim as new and desire to secure by Letters Patent—

HARRY WEARNE.
